UNITED STATES PATENT OFFICE.

EDWARD E. FOSTER, OF BEVERLY, MASSACHUSETTS.

SLED.

Specification of Letters Patent. Patented Jan. 20, 1914.

1,084,697.

Application filed July 8, 1912. Serial No. 708,280.

To all whom it may concern:

Be it known that I, EDWARD E. FOSTER, a citizen of the United States, residing at Beverly, in the county of Essex and State of Massachusetts, have invented certain new and useful Improvements in Sleds; and I do hereby declare the following to be a full, clear, and exact description of the invention, such as will enable others skilled in the art to which it appertains to make and use the same.

The present invention relates to sleds, and more particularly to sleds of that type in which the runners are bowed by the coaster to change the direction of travel of the sled.

The object of the present invention is to produce a sled of the class described, the use of which will require the exercise of skill so as to make the practice of coasting more enjoyable to adults.

To this end the invention consists in the features and combinations of parts herein-after described and set forth in the ap-pended claims.

The various features of the present invention will be readily understood from an inspection of the accompanying drawings, illustrating the preferred embodiment of the invention, in which,

Figure 1 is a plan of the sled; Fig. 2 is a side elevation; and Fig. 3 is a transverse section in elevation on the line 3—3 of Fig. 2, looking toward the rear of the sled.

Referring to the embodiment of the invention illustrated in the drawings, the sled consists of a rigid frame provided with a seat at the rear for the coaster, a pair of conveniently located handles, and a suspension device for supporting a single runner extending in the longitudinal median line of the frame, which runner may be bowed throughout its length to maintain the balance of the coaster and change the direction of travel of the sled.

The frame comprises a pair of parallel tubes 1 suitably secured at their rear ends to a cross-head 2, which supports a seat 3 for the coaster, and at their forward ends to a cross-head 4. The tubes 1 are suitably braced by a transverse tube 5 located between the cross-heads. Fitted to the tubes 1 in front of the seat 3 are a pair of handles 6 to be grasped by the coaster. The frame is also provided with a suspension device for a single runner 7. The suspension device

consists of two turn tables 8 and 9, one of which, the turn table 8, is carried by the rear cross-head 2, and the other one of which, the turn table 9, is carried by the forward cross-head 4. The runner 7 is supported from each member of the suspension device by a pair of angle brackets 10 rigidly secured to both the runner and the turn tables. The turn table 8 is mounted on the cross-head 2 so that it may turn about a fixed vertical axis in the median line of the sled, by a pair of bolts 11 carried by the turn table and projecting through a pair of curved slots 12 formed in the head 2 with their centers of curvature coinciding with the axis of the turn table. The turn table 9 is provided with a vertically arranged pin 13 which projects through a longitudinal slot 14 formed in the head 4 in the median line of the sled. The pin 13 is held for both rotation and sliding movement in the slot 14 by a nut and washer 15.

In order to apply lateral pressure to the runner so as to bow it and enable the coaster 80 seated on the seat 3 to maintain his balance and change the direction of travel of the sled, the turn table 9 is extended laterally on opposite sides of the tubes 1 to form rests 16 for the feet of the coaster, through which 85 the turn table 9 may be operated.

In using the sled, the coaster sits upon the seat 3 with his hands grasping the handles 6 and his feet resting on the rests 16. As shown in Fig. 1, when the rests are moved 90 into the dotted line position the table 9 is turned angularly in the cross-head 4 which applies lateral pressure to the runner and causes it to bow throughout its length. As the runner bows, the turn table 9 moves toward the turn table 8 which, under the influence of the bowed runner, is turned in an opposite direction from that of the table 9. The manipulation of the foot rests 16 to maintain the balance of the coaster is similar to the manipulation of the handles of a bicycle to maintain the balance of the rider. After the balance of the coaster is established, the direction of travel of the sled may be changed by turning the table 9 in 105 one direction or the other. From an inspection of Fig. 1 it is apparent that the points of support of the runner have a fixed lateral relation at all times to the median line of the sled.

While the invention has been illustrated and described as embodied in a sled having

a single runner, it is to be understood that the feature of the invention relating to the supporting of the runner at points having at all times a fixed lateral relation with the median line of the sled and bowing the runner while so supported is applicable to sleds having more than one runner.

What is claimed as new is:—

- 5 1. A sled comprising a single integral runner, and devices for bowing the runner to maintain the balance of the coaster and change the direction of travel of the sled, substantially as described.
- 10 2. A sled comprising a frame provided with a laterally fixed suspension device, a runner supported at two separated points by relatively movable members of the suspension device, and means acting through the suspension device for bowing the runner throughout its length, substantially as described.
- 15 3. A sled comprising a rigid frame, a single runner extending in the longitudinal median line of said frame, a suspension device having two laterally fixed suspension members for said runner rigidly secured to the runner but relatively movable longitudinally in the median line of the frame, and means for relatively moving said devices toward each other to bow the runner, substantially as described.
- 20 25 30

4. A sled comprising a rigid frame, a pair of horizontally arranged, freely rotatable relatively movable, turn tables secured to said frame, a runner rigidly secured to each of said turn tables intermediate its ends, and means for applying lateral pressure to the runner whereby the turn tables are rotated in opposite directions and the runner is bowed throughout its length, substantially as described.

5. A sled comprising a frame, a suspension device carried thereby comprising two members mounted to turn on the frame, a runner rigidly secured to each member of the suspension device, and means to turn one of said members to bow the runner, substantially as described.

6. A coaster sled, having, in combination, a frame provided with a pair of turn tables mounted for relative movement toward and from each other, a runner rigidly secured to each turn table, and means carried by one of the turn tables for permitting the coaster to relatively slide the turn tables toward each other and to turn the tables in opposite directions to bow the runner throughout its length, substantially as described.
